MORRIS D. COHEN, OF NASHVILLE, TENNESSEE.

CAN TOP.

Application filed January 5, 1927. Serial No. 159,186.

My invention relates to can or container tops of that type having an opening in which a pivoted pouring spout is mounted, and it consists in the combinations, constructions and arrangements herein described and claimed.

An object of the invention is to obviate deterioration of the contents of a can of the character described because of the exposure 10 of such contents to the air.

A more specific object of the invention is the provision of quickly and easily releasable means for locking the pouring spout of a can top of the character described in closed 15 position when desired so that the opening in which the pouring spout is mounted will be closed practically air tight, thus obviating such deterioration or impairment of the contents of the can as would result from exposure 20 to the air for any considerable length of time and also obviating accidental opening of the pouring spout and consequent spilling of the contents of the can should the can be overturned when the pouring spout 25 is closed.

A further object of the invention is the provision in a can top of the character described of a novel pouring spout and simple reliable and efficient locking means for holding the spout closed positively when desired and for permitting opening of the spout conveniently and easily when desired.

Other objects and advantages of the invention will be apparent from the following 35 description, considered in conjunction with the accompanying drawings, forming a part of this application, in which

Figure 1, is a plan view of a can top equipped with a pouring spout and one form 40 of locking means for the pouring spout according to the invention, showing the spout locked in closed position,

Figure 2 is a plan view of the can top with the locking means in position to permit opening 45 of the spout but with the spout closed,

Figure 3 is a section along the line 3—3 of Figure 1,

Figure 4 is a section substantially along the line 4—4 of Figure 2 but with the pouring spout open,

Figure 5 is a section along the line 5—5 of Figure 2,

Figure 6 is a plan view of the can top with the locking cover for the pouring spout omitted,

Figure 7 is a perspective view of the pouring spout alone.

Figure 8 is a plan view of another can top equipped with a modified form of pouring spout and locking means therefor, 60 showing the pouring spout locked in closed position,

Figure 9 is a view similar to Figure 8, showing the pouring spout closed but unlocked,

Figure 10 is a section along the line 10—10 of Figure 8,

Figure 11 is a section along the line 11—11 of Figure 9,

Figure 12 is a sectional view of the can 70 top exhibited in Figures 8 to 11, inclusive, with the can top inverted and its pouring spout open, and

Figure 13 is a perspective group view of the modified form of can top with its pouring 75 spout and the pouring spout locking cover removed.

In Figures 1 to 6, inclusive, a can top 1 has a substantially flat sunken or depressed circular portion 2 in which is formed an 80 opening 3. The opening 3 is located between the center and the edge of the depressed portion 2 and may have substantially parallel inner and outer end edges and the outwardly divergent side edges as shown. 85 The depressed portion 2 is formed to provide downwardly offset ledges 4 at the side edges of the opening 3 and with a downwardly offset ledge 5 at the outer end edge of the opening 3. A pouring spout 6 has a flat 90 top 7 from which depends a pair of parallel substantially sector-shaped side members 8 provided at their lower corners with stop extensions or lugs 8^a for engaging with the under surface of the can top to limit the 95 opening movement of the spout. The pouring spout may be formed of a single piece of light gauge metal or other suitable material bent to the desired shape and so that the side edge portions of the top 7 extend laterally of the side members 8 and are adapted to rest on the ledges 4 when the top 100 7 of the pouring spout is disposed in the opening 3. A bendable hinge lug 9 extends from the outer or wider end of the top 7 of the spout and is adapted to be inserted in an opening 10 in the ledge 5 and then bent inwardly under the ledge to hingedly connect the top of the pouring spout with the can top. A lip 11 at the inner end of the 105

110

spout top 7 will be disposed in a slightly larger depression 12 in the depressed portion 2 of the can top when the spout top is in position to close the opening 3 and can be engaged by a finger nail or the like and actuated to swing the pouring spout outwardly from closed position to open position.

A locking cover plate 13 fits rotatably in the depressed portion 2 of the can top and 10 has a thickness approximately equal to the depth of the depression 2. A rivet 14 depends from the center of the plate 13 through a central opening 15 in the depressed portion 2 and pivotally connects the plate 13 with the 15 can top. The plate 13 is cut away at 16 from the outer edge of the plate radially inward for a distance greater than the radial distance from the edge of the plate 13 to the edge of the lip 11 at the inner end of the 20 spout top. The cut away portion 16 of the plate also has a width greater than that of the spout top. The side edges of the cut away portion 16 of the plate may be rolled or turned upward and backward as indicated 25 at 17. The plate 13 is formed with the radial ribs 18 and the concentric circular ribs 19 on the upper face of the plate both to strengthen the plate and to produce finger grip members for convenience in turning the 30 plate 13 in the depressed portion 2 of the can top.

From the foregoing description of the various parts of the device, the operation thereof may be readily understood. When 35 the spout is in closed position, its top will serve as a substantially air tight closure for the opening in the can top. The spout can be locked in its closed position by turning the locking cover plate 13 until the cut away 40 portion 16 is completely out of register with the spout top and the cover plate then will aid in excluding air and moisture from the interior of the can and will positively retain the pouring spout in closed position. The 45 plate 13 is turned until the cutaway portion 16 is above the pouring spout when it is desired to open the spout. The spout will be completely covered by the locking plate when the spout is closed and the locking plate is 50 in locking position, thus safeguarding the spout against injury. It therefore will be obvious that a can having a top construction as hereinbefore described is adapted to hold in practically unimpaired condition granular 55 material, such as ground coffee, which would be impaired if exposed to the action of the atmosphere for any considerable length of time.

The can top shown in Figures 8 to 13, 60 inclusive, is designated 30 and has a circular portion 31 surrounded by a relatively depressed annular portion 32, thus producing a neck 33. The portion 31 has an opening 34 which is similar to the hereinbefore described 65 opening 3. A pouring spout 35 is generally

similar to the spout 6 and has a top 36 and side member 37 and provided with stop extensions or lugs 37a. The top 36 has extending side edge portions 38 adapted to rest on the ledges 39 at the side edges of the 70 opening 34 and also has a bendable hinge lug 40 engageable with an opening 41 in the ledge 42 at the outer end of the opening 34 to hingedly connect the pouring spout 35 with the can top. The spout top 36 does 75 not have an extending lip similar to the lip 11 of the spout 6. A locking cover plate 43 is connected pivotally at its center with the center of the spout top by rivet 44. The locking cover plate has a width greater than 80 that of the spout top 36 and extends flatwise across the spout top and the portion 31 of the can top. However, the width of the locking cover plate 43 is considerably less than the diameter of the portion 31 of the 85 can top.

The neck 33 is provided outwardly of the ends of the opening 34 with segments 45 of screw threads with which internal screw threads on the downturned arcuately curved 90 end portions 46 of the locking cover plate are engageable when the locking cover plate is in position to completely cover the closed spout as shown in Figure 8. The locking cover plate and its downturned neck engaging end portions thus may be turned a mutilated screw cap or in other words, a screw cap having an edge portion or opposite edge portions cut away. Stops 47 on the neck 33 95 cooperate with the portions 46 of the locking cover to limit the turning movement of the latter on the portion 31 of the can top. When the locking cover is in the position shown in Figure 9, it is adapted to serve as a handle 100 for the spout and can be grasped and lifted from the portion 31 of the can top to cause the spout to swing to open position, as shown in Figure 12. The locking cover plate will lie flatwise on the portion 31 of the can top 105 when the spout is closed and when engaged with the neck 33 will positively retain the spout in closed position, whereby a substantially air-tight closure will be produced for the opening 34 in the can top.

Obviously, the invention is susceptible of 115 embodiment in forms other than those which are illustrated in the accompanying drawings and I therefore consider as my own all such modifications and adaptations thereof as fairly fall within the scope of the 120 appended claims.

I claim:

1. A can top having an opening, a pouring spout pivotally attached to the can top and swingable to and from position to close 125 said opening, and a locking cover plate mounted on said top to rotate horizontally and adjustable to and from position to hold said spout closed.

2. A can top having an opening, a pivoted 130

pouring spout for controlling flow through said opening, and a pivoted locking cover plate mounted on said top to rotate horizontally and adjustable to and from position 5 to overlie said spout and to hold said spout in closed position.

3. A can top having a depressed substantially flat circular portion, formed with an opening, a pouring spout having a top 10 hinged to said depressed portion at one end of the opening and swingable outwardly from position to close said opening, a locking cover plate fitting in the depressed portion of the can top and pivotally connected 15 with the can top, said locking cover plate having a cut away portion of greater length and width than said spout top and in position to permit opening of the spout there-through when the cover plate has been 20 turned on the depressed portion of the can top to a certain position.

4. A can top having a depressed substantially flat circular portion, formed with an opening, a pouring spout having a top 25 hinged to said depressed portion at one end of the opening and swingable outwardly from position to close said opening, a locking cover plate fitting in the depressed portion of the can top and pivotally connected 30 with the can top, said locking cover plate having a cut away portion of greater length and width than said spout top and in position to permit opening of the spout there-through when the cover plate has been 35 turned on the depressed portion of the can top to a certain position, said locking cover plate having ribs thereon serving to strengthen the plate and also as finger grip members for turning the cover plate on the 40 depressed portion of the can top.

5. A can top having a depressed substantially flat circular portion formed with an opening, a pouring spout having a top 45 hinged to said depressed portion at one end of the opening and swingable outwardly from position to close said opening, a locking cover plate fitting in the depressed portion of the can top and pivotally connected 50 with the can top, said locking cover plate having a cut away portion of greater length and width than said spout top and in position to permit opening of the spout there-through when the cover plate has been 55 turned on the depressed portion of the can top.

can top to a certain position, said locking 60 cover plate having ribs thereon serving to strengthen the plate and also as finger grip members for turning the cover plate on the depressed portion of the can top, certain of said ribs extending along circles parallel 65 with the edge of the cover plate.

6. A can top having a depressed substantially flat circular portion, formed with an opening, a pouring spout having a top 70 hinged to said depressed portion at one end of the opening and swingable outwardly from position to close said opening, a locking cover plate fitting in the depressed portion of the can top and pivotally connected 75 with the can top, said locking cover plate having a cut away portion of greater length and width than said spout top and in position to permit opening of the spout there-through when the cover plate has been 80 turned on the depressed portion of the can top to a certain position, said opening being at one side of the center of the depressed portion of the can top and said pivotal connection between the cover plate and the can top being at the center of both the cover 85 plate and the depressed portion of the can top.

7. A can top having a depressed substantially flat circular portion, formed with an opening, a pouring spout having a top 90 hinged to said depressed portion at one end of the opening and swingable outwardly from position to close said opening, a locking cover plate fitting in the depressed portion of the can top and pivotally connected 95 with the can top, said locking cover plate having a cut away portion of greater length and width than said spout top and in position to permit opening of the spout there-through when the cover plate has been 100 turned on the depressed portion of the can top to a certain position, the thickness of said cover plate and the depth of said depressed portion of the can top being approximately the same.

8. A can top having an opening, a pouring spout pivotally attached to said top to swing into and out of said opening, and a locking cover plate mounted to rotate horizontally on said can top and extend over 105 said spout when the latter is in closed position to hold the spout in closed position.

MORRIS D. COHEN.
